Attorney

UNITED STATES PATENT OFFICE

JAMES J. WELCH, OF AUSTIN, MINNESOTA

BURIAL VAULT

Application filed November 21, 1930. Serial No. 497,086.

This invention relates to improvements in burial vaults or coffin receptacles.

The main object of the invention is to provide a burial vault adapted to be set in the ground and including a sealed coffin chamber and a sealed air chamber above the coffin chamber, the latter being exposed to the sun and air whereby the air therein and in the casket chamber is kept dry and warm.

10 Another object is to provide means in both the casket and air chamber whereby the effective surfaces of the wall or closure between the chambers are increased in size to greatly facilitate the warming and drying of the air 15 in the casket chamber, the said wall or closure being for this purpose provided with pyramids or projections extended upwardly and downwardly into the air chamber and casket chamber respectively.

20 A further object is to provide a burial vault of the character described in a simple and durable form.

The foregoing and other objects together with means whereby the same may be carried 25 into effect will best be understood from the following description of a preferred embodiment of the invention taken in connection with the accompanying drawings wherein:

Figure 1 is a plan view of the vault.

30 Figure 2 is a longitudinal vertical section of the vault.

Figure 3 is a vertical cross section thereof.

Referring now more particularly to the drawings the reference character 1 designates 35 the casket chamber comprising the receptacle 2 formed of the bottom 3, opposed ends 4 and opposed sides 5, the top of the receptacle being open. The receptacle is constructed of cement or the like, is waterproof and air tight, 40 and is of such size that the coffin will set therein with a space remaining entirely around it to permit the free circulation of air, the said coffin for this reason being set on the raised transverse ribs 6 on the bottom 3. Inwardly 45 extending ledges or shoulders 7 are provided on the sides 5 at some distance below their upper margins and a lower plate or closure 8 is seated on these shoulders to close the casket chamber 1. After the casket (not shown) 50 has been placed in the chamber 1 and the plate

8 put in place a layer of fresh or plastic cement or sealing material 9 is poured over the said plate 8 to make the chamber 1 air tight. A rectangular form 10 comprising the opposed ends and sides 11 and 12 respectively is provided and the same is relatively smaller than the inner dimensions of the receptacle 2 whereby a space will be left between the ends and sides of the receptacle and form when the latter is set upon the seal 9 placed over the plate 8. This space is filled as shown at 13 with a sealing material similar to that before described. An upper plate 14 is set within the form 10 upon the sealing material 9 and is held thereby in spaced relationship above the plate 8. A cover 15 is provided, the same having a marginal flat edge 16 and the center upwardly arched or convexed portion 17. A lip or tongue 18 is provided around the underside of the cover 15 and is so disposed that it will fit downward and seat in the seal or filling around the form 10 to make the joint between the cover and receptacle air and water tight. The flat edge 16 extends beyond the margins of the receptacle 2 and contacts the same as shown, the upper edges of the receptacle being preferably covered with fresh cement before the cover is put in place to further seal the cover in place. A sealed air chamber 19 is thus provided between the plate 14 and cover 15 and within the form 10.

The burial vault thus formed is set in the ground with the flat edge 16 of the cover 15 disposed flush with the surface of the ground 85 to facilitate the mowing of the grass around the vault.

The cover 15 is thus exposed to the sun and air causing the air in the air chamber 19 to become heated and to remain dry. This warm air then heats the air in the coffin chamber 1 and causes the same to remain dry and warm at all times as will be understood. To facilitate this warming and drying of the air in the chamber 1 the lower plate 8 is provided with a plurality of spaced depended pyramids or projections 20 on its underside and the upper plate 14 is similarly provided with upwardly extended pyramids or projections 21. The effect of these pyramids 20 and 21

is to increase the effective surfaces of the plates 8 and 14 exposed to the air in the chambers 1 and 19 thus facilitating the absorption and radiation of the heat from the air chamber 19 into the coffin chamber 1.

5 The plates 8 and 14 are formed of cement similar to the receptacle 2 and the cover 15 is made of marble, granite or compositions thereof, the entire vault being reinforced with rods 22 and metal fabric or mesh 23 in the 10 usual manner. The cover 15 is provided with a depression 24 adapted to receive a suitable inscribed marker or heat stone (not shown).

15 While I have herein set forth a certain preferred embodiment of my invention it is understood that I may vary from the same in minor structural details so as best to construct a practical device for the purpose intended, not departing from the spirit of the 20 invention and within the scope of the appended claims.

I claim:

25 1. In a device of the kind described, a receptacle, a lower plate seated in the receptacle beneath the upper margins thereof, a plastic filling over the top plate, an upper plate seated in the plastic filling, and a cover mounted on the receptacle.

30 2. In a device of the kind described, a receptacle, a lower plate seated in the receptacle beneath the upper margins thereof, a plastic filling over the top plate, an upper plate seated in the plastic filling, and a cover mounted on the receptacle, and means where- 35 by the effective upper and lower surfaces of the upper and lower plates respectively are increased.

35 3. In a device of the kind described, a receptacle, a lower plate seated in the receptacle below the upper margins thereof, a plastic filling over the lower plate, an upper plate seated on the said filling, a cover mounted over the receptacle above the said upper plate, projections extended downward from 45 the underside of the lower plate and similar projections extended upwardly from the upper side of the upper plate.

In testimony whereof I affix my signature.
JAMES J. WELCH.
